UNITED STATES PATENT OFFICE

PANFILO TROMBETTA, OF SCHENECTADY, NEW YORK, ASSIGNOR TO GENERAL ELECTRIC COMPANY, A CORPORATION OF NEW YORK

ELECTROMAGNETICALLY OPERATED SWITCH

Application filed July 18, 1927. Serial No. 206,466.

This invention relates to electromagnets having switch mechanism operated thereby and provides an improved form of switch which is convertible to either the normally 5 open or the normally closed type, an improved mounting arrangement of the switch on the electromagnet, as well as an improved mechanism for operatively connecting the movable switch element and the movable 10 magnetic member of the electromagnet.

The improvements of the present invention are particularly advantageous where the switch is used to control the energizing circuit of the electromagnet during the operation thereof. For example, it is common practice in direct current service to reduce the energization of an electromagnet upon operation of the magnetic member to the attracted position by providing an auxiliary 20 switch operable by the magnetic member to insert a resistance in the energizing circuit of the electromagnet. The present invention provides an improved switch that readily may be arranged to either close its contacts 25 or open its contacts upon operation of the electromagnet and the improved operating mechanism of the switch requires only a very slight final movement of the magnetic member of the electromagnet for effecting operation 30 of the switch. Moreover, the operating mechanism is such that the switch actually may be operated after the completion of the slight final movement of the magnetic member of the electromagnet. In addition, both 35 the switch and the operating mechanism may readily be mounted directly on the frame of the electromagnet thereby permitting a simplified and compact mounting of the electromagnet and the control switch mechanism 40 therefor.

Other advantageous features of the invention will appear from the following description of the accompanying drawings in which Fig. 1 is a plan view of an electromagnet 45 provided with the improved form of controlling switch mechanism and operating mechanism of the present invention, the switch being of the normally closed type; Fig. 2 is a sectional view of the electromagnet and switch mechanism of Fig. 1 show-

ing more clearly the details of construction; Fig. 3 is a top view of the electromagnet and the normally closed switch of Fig. 1; Figs. 4 and 5 are circuit diagrams showing schematically the normally closed control switch 55 arranged to control the energization of the operating windings of the electromagnet upon operation of the electromagnet; Fig. 6 is a plan view of the switch arranged to be normally in the circuit opening position and 60 operable to the circuit closing position upon operation of the electromagnet; Fig. 7 is a sectional view of the electromagnet of the normally open switch of Fig. 6; Fig. 8 is a top view of the electromagnet and normally 65 open switch; and Fig. 9 is a circuit diagram showing the connections used for enabling the normally open switch to connect the portions of the operating windings of the electromagnet in parallel circuit after operation 70 thereof.

Referring to Fig. 1, the electromagnet 10 is shown of the improved form described and claimed in my copending application Serial No. 189,878, filed May 9, 1927, which became 75 Patent No. 1,696,615 on December 25, 1928, with which the improved form of switch mechanism and operating mechanism of the present invention is particularly adapted for use. It will be understood, however, that the 80 improvements of the present invention may be applied to other suitable forms of electromagnet. Briefly, the electromagnet 10 comprises a laminated frame 11 having the laminations held together by the angle supporting pieces 12. The frame 11 is provided with an opening 13 on one side thereof through which the movable magnetic member or plunger 14 operates upon energization of the energizing windings 15. The plunger 14 has 85 an enlarged head 16 providing the projecting shoulders 17 on either side thereof for magnetically sealing with the sides of the frame 11 adjacent the opening 13 when the plunger 90 is operated to the attracted position.

The switch mechanism 18 is arranged to be operated by the final movement of the plunger 14 to the attracted position through the agency of the operating member 19. The switch mechanism 18 in the preferred form 100

shown comprises the two sets of stationary spaced apart contact elements 20 and 21 with which the movable bridging contact elements 22 and 23 respectively cooperate. The stationary spaced apart contacts 20 and 21 are mounted upon the base 24 formed of insulating material, such as bakelite or the like, by means of screws 25 and 26. The base 24 is secured to a yoke member 27 with the insulating sheet 28 interposed therebetween by means of the bolts 29. The whole switch mechanism 18 is mounted directly upon the frame of the electromagnet 10 by means of the bolts 30 which pass through suitable holes formed in the electromagnet frame 11 and clamp the yoke 27 securely thereto.

As may be more clearly seen in Fig. 3, the movable contact members 22 and 23 bridge between the stationary contacts 20 and 21 although a single stationary contact with a cooperating movable contact may be employed if desired. The movable contacts 22 and 23 are yieldingly mounted upon the movable contact arm 31 by means of the square post 32 and the springs 33 which are interposed between the contacts and the washer 34 held upon the end of the post 32 by the bolts 35. The two movable contacts 22 and 23 are suitable for controlling the same circuit, one serving as an arcing contact and the other as the main current carrying contact or the contacts may control separate circuits if desired.

The movable contact arm 31 is arranged to be mounted in two different cooperating relations with the stationary contacts 20 and 21, one relation resulting in the normally closed switch shown in Fig. 1 and the other relation resulting in the normally open switch shown in Fig. 5. In the arrangement of Fig. 1 the movable contact arm 31 is pivotally mounted upon the pin 36 which is supported at its ends by the spaced apart arms 37 which preferably are formed on the base 24. A double wound biasing spring 38 having its outer ends 38A seated in the recesses 39 formed in the base 24 and its inner looped end 38B engaging with the downturned tongue 40 on the contact arm 31 serves to bias the contact arm to carry the bridging contacts 22 and 23 into engagement with the respective contacts cooperating therewith.

The operating member 19 for the switch mechanism is formed of a lever 41 preferably of channel shape as shown in Fig. 3 having a strip 42 secured thereto as by riveting with one end of the strip bent up to form a projecting substantially knife-edge support for pivotally mounting the lever arm 41 in the open slot 43 which is formed in the side of electromagnet frame 11 adjacent the opening 13. The open slot 43 is formed by providing a notch in each of the laminations comprising the frame 11 which, when superimposed, forms an open slot across the outside of the frame. The ends of the slots are

closed by the angle supports 12, thus preventing lateral displacement of the lever arm 41. The other end of the strip 42 is bent over to form a stop 44 engaging with the adjacent side of the electromagnet frame 11 as indicated in Fig. 2. The biasing spring 45 is connected between the stop 44 and the tongue 27' extending from the yoke member 27. Spring 45 serves to hold the operating member 19 in pivotal engagement with the electromagnet frame 11 and also biases the member 19 to a position in which the stop 44 engages with the side of the electromagnet frame with the end of the operating member 19 on the opposite side of the pivotal support in spaced relation between the side of the frame 11 and the head of the plunger 14. This end of the operating member 19 thus is in the path of movement of the offset projecting shoulder 17 so as to be engaged thereby upon the final movement of the plunger 14 to the attracted position. The other end of the operating member 19 is yieldingly connected with the switch operating arm 31 by means of the spring 46. One end of the spring 46 is hooked directly into a hole formed in the end of the operating member 19 and the other end of the spring is hooked into an eye member 47 which is detachably secured to the switch arm 31 by means of the removable pin 48. The arrangement of the springs 45 and 46 is such that when the spring 45 maintains the stop 44 on the pivoted operating member 19 in engagement with the magnet frame as shown in Figs. 1 and 2, there is relatively little strain or tension in the spring 46, the latter serving simply as a yielding connection between the operating member 41 and the switch mechanism. Moreover, with the double wound bias spring 38 for the switch mechanism having its outer ends 38A anchored in the recess 39 formed in the base 24 and its inner looped end 38B engaging with the downturned tongue 40 on the contact arm 31 as shown in Figs. 1, 2 and 3, the ends 38A and 38B of the spring are maintained under a tension to move together and thereby exert a force tending to rotate the contact arm 31 in a counter-clockwise direction about the pivot pin 36. In this way the switch contacts 22 and 23 are biased to the circuit closed position.

The operation of the normally closed switch as shown in Figs. 1, 2 and 3 by the electromagnet as follows: Upon suitable energization of the operating windings of the electromagnet the plunger 14 is moved to the attracted position in which the enlarged head 16 of the plunger bridges across the opening 13 formed in the side of the electromagnet frame 11. Just before the plunger 14 engages with the frame 11, the offset shoulder 17 is arranged to strike the end of the operating member 19 which pivots upon its protecting support in the slot 43 and

thereby sets up a strain in the resilient connecting spring 46 tending to effect operation of the switch arm 31 to the circuit opening position.

5 Due to the high speed at which the projection 17 strikes the operating member 19, the inherent inertia of the switch arm 31 carrying the bridging contacts 22 and 23, and the resilient connection between the operating member and the switch arm, the actual movement of the bridging contacts 22 and 23 to the circuit opening position may occur after the completion of the movement of the plunger 14 to the attracted position. The 10 resilient connection between the operating member and the switch arm also insures that the shock produced upon the impact of the head of the plunger 14 with the operating member 19 is not transmitted directly to the switch arm 31. The separate mounting of the operating member 19 directly upon the electromagnet frame 11 insures that the end of the operating arm is in the proper spaced relation in the path of the head of the plunger 14 to produce operation with a minimum final movement of the plunger. In fact, the final movement required for operation of the operating arm 19 may be a very small fraction of an inch whereas a much larger travel 30 of the plunger would be required with the operating member 19 mounted in the usual manner.

It will be understood that the electromagnet is mounted so that upon deenergization 35 of the operating winding the plunger 14 falls from the attracted position and thereby disengages the offset shoulder 17 from the operating member 19. The biasing spring 45 serves to return the operating member 19 into the position shown in the drawings, thereby 40 relieving the strain in the connecting spring 46. This permits the biasing spring 38 to return the switch arm 31 to its normal circuit closing position as indicated in the drawings.

While the improved form of switch mechanism shown may be employed to control any circuit or circuits desired, it is particularly adapted to control the energizing circuit 50 of the electromagnet itself. Thus, as diagrammatically shown in Fig. 4, the normally closed switch mechanism 18 may be employed to insert a resistance R in the circuit of the operating windings 15 of the electromagnet when the plunger 14 is operated to the attracted position. In this way the energy input to the electromagnet may be materially reduced after the plunger 14 has completed its working stroke and has substantially closed the magnetic circuit of the electromagnet.

The operating winding control arrangement shown in the simplified diagram of Fig. 5 may be employed instead of the resistance control arrangement of Fig. 4, if desired. As

shown in Fig. 5, the normally closed switch mechanism 18 is connected to normally short circuit a portion of the operating winding 15 of the electromagnet. The short circuited portion preferably is of relatively high resistance, while the remaining portion of the operating windings is arranged to supply the ampere turns required to effect operation of the movable magnetic member to the attracted position. Thereupon the switch mechanism 18 operates to insert the high resistance portion of the operating windings in series circuit with the operating portion. As a result the operating current of the electromagnet is materially reduced when the movable magnetic member is in the attracted position with a corresponding reduction in the watts input to the electromagnet.

To convert the switch mechanism with which the electromagnet is provided from the normally closed type illustrated in Figs. 1, 2, and 3 to the normally open type illustrated in Figs. 6, 7, and 8, it is only necessary to shift the pivot supporting pin for the switch arm 31 and the supporting pin 48 for the eye member 47 and rearrange the engagement of the biasing spring 38 with the base 24 and the switch arm 31. Thus, the pivot pin 36 is shifted to the holes in the switch arm previously occupied by the pin 48 and to the corresponding holes 49, which are formed in the arms 37 of the base 24 and the supporting pin 48 for the eye member 47 is shifted to the holes in the switch arm 31 formerly occupied by the pivot pin 36. The switch mechanism then assumes the normally open form illustrated in Figs. 6, 7, and 8 when the biasing spring 38 is assembled upon the pivot pin 36 with its inner looped end 38B in engagement with the upper side of the base 24 and the two outer ends 38A of the spring in engagement with the shoulder on the switch arm 31 as indicated in Figs. 5 and 7. In this modified arrangement the biasing spring 38 is assembled with the ends 38A and 38B of the spring under compression so as to tend to move apart and thereby functions to bias the switch gear 31 to carry the bridging contacts 22 and 23 out of engagement with the stationary contact elements 20 and 21. The spring 45 functions to hold the operating member 19 in its pivotal support in the slot 43 in the electromagnet frame 11 with the end of the operating member in the path of the shoulder 17 on plunger 14 in the same manner as previously described. The spring 46 extending between the end of the operating arm 19 and the eye member 47 also serves to provide a resilient connection between the operating member 19 and the switch mechanism to absorb shock and permit operation of the switch arm to follow the completion of the stroke of the plunger as set forth above.

The operation of the switch mechanism in its modified form is as follows: The engagement of the offset shoulder 17 and the head of the plunger 14 upon the final movement 5 of the plunger to the attracted position sets up a strain in the connecting spring 46 which operates the switch arm 31 to carry the bridging contacts 22 and 23 into circuit closing engagement with the cooperating stationary 10 contact elements 20 and 21. With the electromagnet mounted to permit the plunger 14 to drop away from the frame 11 upon deenergizing of the operating winding 15, the operating member 19 is released. This 15 permits the biasing spring 38 to return the switch arm 31 to its normal circuit opening position.

As shown in the circuit diagram of Fig. 9, the normally open switch mechanism of 20 Figs. 6, 7, and 8 may be employed to connect a plurality of operating windings for the electromagnet in multiple circuit relations upon operation of the plunger 14 to the attracted position. This connection arrangement 25 is of particular advantage where the electromagnet is operated in series with other devices such as motors in a direct current circuit for controlling friction brakes, switches or the like, as it permits the energizing 30 ampere turns of the electromagnet to be decreased when the plunger 14 is in the attracted position.

With the connections as shown in Fig. 9, the lower portion of the divided operating 35 winding 15 is energized initially and serves to supply the attractive force necessary to effect operation of the plunger 14 to the attracted position. Preferably the lower portion of the operating windings is formed of 40 a large number of turns and consequently has a relatively high resistance. With the plunger 14 in the attracted position, a very much reduced attractive force is sufficient to hold the plunger in the attracted position. 45 Thus the switch mechanism 18 is arranged to connect the upper portion of the operating windings in parallel circuit with the lower portion. With the upper portion of the operating windings of relatively few 50 turns and relatively low resistance, the major portion of the current in the series circuit will flow through the upper portion while the lower portion of the operating windings will be energized in accordance with the voltage drop across the upper portion. In this 55 way, the effective ampere turns of the operating windings may be materially reduced with a corresponding reduction in the watts input.

60 While I have illustrated and described a preferred form of switch mechanism and operating mechanism embodying the improvements of the present invention, it will be understood that changes and modifications may be made therein without depart-

ing from the spirit and scope of the invention.

What I claim as new and desire to secure by Letters Patent of the United States is:

1. The combination of an electro-magnet 70 having a magnetic member movable to the attracted position upon energization of the electromagnet, contacts operated by the said movement of said magnetic member, adjustable biasing means whereby said contacts 75 may be adjusted at will so as to be either normally open or normally closed, and cooperating adjustable connections between the magnetic member and contacts whereby said contacts may be either closed or opened upon 80 movement of the magnetic member to the attracted position depending upon the adjustment of said connections.

2. The combination of an electromagnet 85 having relatively movable magnetic members with an air gap therebetween arranged substantially to be closed upon energization of the electromagnet, and switch mechanism associated with the electromagnet and having an operating member mounted on one of the 90 magnetic member and disposed in the air gap therebetween closely adjacent said one magnetic member to be operated during final movement of the magnetic members to close 95 said air gap.

3. The combination of an electromagnet having a magnetic structure including a frame and a cooperating magnetic plunger provided with an enlarged head for magnetically sealing with the frame when operated into the attracted position, and a switch mechanism for controlling the electromagnet mounted on the frame and having an operating member separately mounted on the frame and disposed in the path of movement of the said enlarged head to be operated thereby upon the final movement of the magnetic plunger into the attracted position. 100

4. The combination of an electromagnet 110 having a magnetic frame and a cooperating magnetic plunger provided with an enlarged head magnetically sealing therewith, and a switch mechanism mounted on the frame of the electromagnet and having a separately mounted operating member resiliently connected with the switch mechanism and extending into the path of movement of said enlarged head to be operated thereby upon the final movement of the magnetic plunger 115 to the attracted position.

5. The combination of an electromagnet having a magnetic structure including a frame provided with an opening therein and a movable plunger operable in said opening and provided with an enlarged head magnetically sealing with the sides of the frame adjacent said opening when the plunger is in the attracted position, a switch mechanism for controlling the electromagnet removably mounted on the frame thereof and having 120 125 130

means for biasing the switch mechanism to a predetermined circuit controlling position, an operating member having a knife-edge mounting on the frame adjacent said opening with the end of the operating member extending in the path of movement of said enlarged head to be operated thereby upon the final movement of the plunger to the attracted position, and a yielding connection between the operating member and the switch member to permit operation of the switch mechanism against its bias to follow operation of the said operating member.

6. The combination of an electromagnet having a magnetic frame provided with an air gap therein and a slot in the frame adjacent said air gap, a magnetic plunger movable in said air gap to the attracted position and having an enlarged head for magnetically sealing with the sides of the frame adjacent said air gap, switch mechanism mounted on the frame, and an operating member for the switch mechanism provided with a knife-edged projection for pivotally mounting the operating member in the said slot with a portion of the operating member extending into the path of movement of said enlarged head to be engaged thereby upon operation of the magnetic plunger to the attracted position.

7. The combination of an electromagnet having a magnetic frame provided with an opening in one side thereof and provided with a slot in the frame adjacent said opening, a movable magnetic plunger operable through said opening and having lateral projections cooperating with the sides of the frame adjacent said opening, switch mechanism mounted on the frame, an operating member therefor provided with a projection intermediate its ends for pivotally mounting the operating member in said slot in the frame independently of the mounting of the switch mechanism with one end of the operating member in the path of movement of one of said lateral projections of the plunger, and a resilient connection between the other end of the operating member and the switch member for permitting movement of the switch member to follow movement of the operating member upon operation of the magnetic member to the attracted position.

8. The combination of an electromagnet having a laminated magnetic frame of rectangular shape provided with an opening in one side thereof and an open slot in the laminations adjacent said opening, a movable magnetic member operable through said opening in the frame and having lateral projections magnetically cooperating with the sides of the frame adjacent the opening when the member is in the attracted position, switch mechanism removably secured to another side of the frame of the electromagnet, an operating member provided with a projection in-

termEDIATE its ends for pivotally mounting the member in the said open slot in the frame with one end of the member extending into the path of movement of one of the projections of the movable magnetic member to be operated thereby upon the final movement of the magnetic member into the attracted position, and a spring connected between the other end of the operating member and the switch mechanism and forming a yielding operating connection therebetween permitting movement of the switch mechanism to follow movement of the operating member upon operation of the movable magnetic member to the attracted position.

9. An electromagnet having controlling switch mechanism therefor provided with interchangeable pivotal supports and operating connections for permitting operation to either the circuit opening position or the circuit closing position upon operation of the electromagnet.

10. An electromagnet having a switch mechanism associated therewith for varying the energizing circuit of the electromagnet during operation thereof, said switch mechanism having a movable circuit controlling member and operative connections between the movable circuit controlling member and the movable magnetic member of the electromagnet arranged to be assembled in two different relations, one for effecting closure of a circuit upon energization of the electromagnet and the other for effecting the opening of a circuit upon energization of the electromagnet. 100

11. The combination of an electromagnet having a movable magnetic member, switch mechanism mounted on the electromagnet and having a movable circuit controlling member connected to be operated upon the final movement of the movable magnetic member to the attracted position, the said connections being adjustable to effect movement of the movable circuit controlling member to either the circuit opening or the circuit closing position upon operation of the movable magnetic member to the attracted position. 110

12. The combination of an electromagnet having a movable magnetic member, a switch mechanism including a fixed switch element mounted on the electromagnet, a cooperating movable switch element adapted for pivotally mounting on either of two different axes and having adjustable biasing means for establishing correspondingly different circuit controlling relations with the fixed switch member, an operating member for the switch separately mounted on the electromagnet to be operated by the movable magnetic member thereof, and a spring adjustably connected between the said operating member and the movable switch element for operating the 115
120
125
130

same in each of said circuit controlling relations.

13. The combination of an electromagnet having a movable magnetic member, a switch for varying the energizing circuit of the electromagnet during operation thereof, said switch comprising an insulating base removably mounted on the electromagnet and having a fixed switch element secured thereto, a cooperating movable switch element, means for mounting said movable switch element on either of two different axes to establish correspondingly different circuit controlling relations with said fixed switch element, one forming a normally closed switch and the other forming a normally open switch, an operating member for the switch separately mounted upon the electromagnet and extending into the path of movement of said movable magnetic member to be operated thereby upon final movement thereof to the attracted position, and a spring for operatively connecting the operating member with the movable switch member in each of said circuit controlling relations.

14. The combination of an electromagnet having a laminated magnetic frame of rectangular shape provided with an opening in one side and having a notch formed in each lamination to provide a groove in the side of the frame adjacent said opening, a pair of angle supports secured on the opposite sides of said one side of the frame to bridge said opening and close the ends of said slot, a movable plunger operable through said opening between said supports and having projections for magnetically cooperating with the sides of the frame adjacent the opening when the plunger is in the attracted position, a switch mechanism removably mounted on another side of the frame of the electromagnet adjacent the side having said groove therein, an operating member for the switch mechanism having a projection for pivotally mounting the operating member in said groove with one end of the operating member disposed in spaced relation between the side of the frame and one of the lateral projections of said plunger to be engaged by said projection upon the final movement of the plunger to the attracted position, a spring resiliently connecting the other end of the operating member with the switch mechanism, and a stop on the operating member engaging with said other side of the frame for maintaining the operating member in a predetermined spaced relation with the frame.

In witness whereof, I have hereunto set my hand this 15th day of July, 1927.

PANFILO TROMBETTA.
